UNITED STATES PATENT OFFICE.

RICHARD F. BEUTLICH, OF CHICAGO, ILLINOIS, ASSIGNOR TO TWENTIETH CENTURY MACHINERY CO., OF CHICAGO, ILLINOIS, A CORPORATION OF WISCONSIN.

BOTTLE-WASHING MACHINE.

1,144,023.

Specification of Letters Patent. Patented June 22, 1915.

Application filed January 23, 1915. Serial No. 3,904.

To all whom it may concern:

Be it known that I, RICHARD F. BEUTLICH, a citizen of the United States, residing at Chicago, in the county of Cook and State of Illinois, have invented a new and useful Improvement in Bottle-Washing Machines, of which the following is a specification.

My invention relates to an improvement in the class of machines which are known in the practical art as bottle-soaking machines, because of their purpose of soaking the labels off the bottles as well as washing and rinsing the latter.

The primary object of my invention is to improve the type of bottle-washing machine exemplified in Letters Patent No. 1,018,046, granted February 20, 1912, to S. L. Goldman and Letters Patent No. 1,130,015, granted March 2, 1915, to J. T. H. Paul, particularly in the matters of speeding the operation by rendering the travel of the endless bottle-carrier continuous, instead of intermittent, reducing the work of the pump, thereby also keeping the water-spraying nozzles from clogging, and effectually disposing of the labels washed from the bottles.

In the accompanying drawings, Figure 1 is an outline view of the machine in side elevation, partly broken and showing parts by dotted representation; Fig. 2 is an enlarged section on line 2—2, Fig. 1, and Fig. 3 is a similar section but taken on line 2—2 at the side of the machine opposite that presented in Fig. 1; Fig. 3^a is a broken view in elevation and partly sectional, showing certain details; Fig. 4 is a section on line 4—4, Fig. 6; Fig. 5 is a broken view in section on line 5—5, Fig. 6, and Fig. 6 is a similar view in section on line 6—6, Fig. 5, 40 or on line 6—6, Fig. 4.

In its general construction, the machine is the same as that described in said patents. The tank 7, in the present instance, however, contains only two compartments separated by a partition 8 and forming, respectively, the hot cleansing-water or solution compartment 9 and the fresh rinsing-water compartment 10. A hood 11 extends in elevated position over the tank, lengthwise about which an endless-chain bottle-carrier 12 travels over sprockets, indicated at 13, the shaft of a sprocket, shown at the discharge-end of the machine where a chute 15 is represented in Fig. 1, carrying a gear-wheel indicated at 14. The two chains of the endless

carrier are connected together at intervals by cross-bars 16 (Figs. 2 and 3), each of which is provided with a series of pockets 17 for seating bottles 18 in inverted position, and centering them relatively to funnel-like nozzles 19 in the lower extensions of the pockets. Each bar has bracket-extensions 16^a of the conveyer-chains bolted to its opposite ends, and on these chains are journaled rollers 16^b to travel on tracks 20 supported on angle-posts 20^a (Figs. 2 and 3) rising at intervals on opposite sides of the tank. An electric motor 21 drives a centrifugal pump 22, which takes the hot water from the compartment 9 through a pipe 23 and forces it through a pipe 24 terminating at its upper end in a manifold 25 extending along the top of the tank below the plane of bottles traveling over the latter, this manifold containing a partition 26 dividing it into hot and cold water sections; and the pump also forces hot water from the tank-compartment 9 through a valved pipe 24^a supplying a series of spraying pipes 25^a extending parallel with the manifold 25 above the plane of the aforesaid bottles, each of these spraying-pipes extending lengthwise over a different row of the bottles. Fresh water is supplied to the tank-compartment 9, to be mixed therein with a suitable cleansing substance, if desired, and to be heated as hereinafter described, through a pipe 27 containing a valve at 28 and a valve at 29; and from this pipe lead a branch-pipe 30 into the fresh-water compartment of the manifold 25 and a branch-pipe 31 to a series of spraying-pipes 25^b extending in line with the pipes 25^a.

The parts as thus far described are substantially the same as the corresponding parts in the machines of the aforesaid patents.

The endless carrier 12 is driven continuously by a belt-connection with the motor-shaft, as indicated at 32 in Fig. 1, a shaft 33 journaled in bearings on a side of the tank and provided on one end with a worm 34 meshing with a worm-wheel, indicated at 35, on a shaft 36 carrying a pinion 37 meshing with the gear 14.

The manifold 25 is connected at intervals along its length, as hereinafter described, with another manifold 38 (Fig. 3) extending along the opposite inner side of the tank; and both of these manifolds are supported,

105

110

to be reciprocated, on concave rollers 39 journaled in suitable position on the inner sides of the opposite tank-walls near their upper edges. The pipe 24, which has a 5 flexibly jointed connection at 24^b with the manifold 25 and a similar connection at 24^c with the discharge side of the pump, contains an intermediate expansion, telescopic or slip-joint 24^d to adapt the pipe to yield 10 with the reciprocal movements, hereinafter described, of the manifolds 25 and 38; and a pipe 38^a, having a flexibly jointed connection at 38^b (Figs. 3 and 3^a) with the manifold 38 and containing a slip-joint 38^c, supplies steam 15 from a pipe 38^d to the last-named manifold. A similar slip-joint is provided at 30^a (Fig. 1) in the pipe 30. The connections between the headers 25 and 38 consist, each, of tubes 40 and 41, these two tubes extending parallel 20 and being integral with each other and closed at their respectively opposite ends. The manifold 25 is connected with the open end of the tube 40 and the manifold 38 is similarly connected with the open end of the 25 tube 41. At intervals along the top of each tube 40, these intervals corresponding with those at which the flaring nozzles 19 depend in a series on each cross-bar 16, are provided threaded holes, in which are screwed nozzles 30 42; and steam-jets 43 are screwed into openings in each tube 41 to register with and project a slight distance into the open bases of the nozzles, to coöperate with the latter in an injector-like manner. The jets are closed 35 at their bases by screw-caps 43^a.

The tank-compartment 9 being filled to the desired level with water supplied through the pipe 27, after which the valve 28 is closed, and the valve 29 being open, steam 40 entering the tubes 41 and the motor running to drive the pump 22 and the shaft 33, the endless bottle-carrier 12 is driven slowly and continuously, while the steam is discharging through the jets 43 to inject water through 45 the nozzles 42 into the nozzles 19 and thence into the bottles 18 as the members thereof in each transverse series register, in the travel of the carrier, with the nozzles 42 below them. In the meantime the spray-pipes 25^a 50 and 25^b are spraying water downwardly against and over the longitudinal rows of bottles as they pass to cleanse their exteriors and wash off the labels. As will be seen, the steam heats the cleansing water, coming from 55 the tubes 40, to the desired temperature, and its injector-action relieves the pump of considerable work in raising the water; in fact it enables the work to be performed by one pump where a plurality of pumps would 60 otherwise be required.

To effect thorough cleansing of the interiors of the bottles, it is necessary that they be subjected to the action of the nozzles each 65 continuously for a somewhat prolonged period in the travel of the carrier. To effect

this, I cause the manifolds 25 and 38, and therefore their connecting tubes carrying the jetting members, to travel at the speed of the carrier for some distance, whereby the respective nozzles 42 and 19 remain in registration with bottles during such period, after which these manifolds are quickly retracted on their carrying rollers 39 and the advance with the carrier is then repeated. This operation is accomplished by a cam-groove 43 formed in the face of the worm-wheel 35, or provided on the worm-wheel shaft, and in which travels a roller or stud 44 on one end of a lever 45 extending from a rock-shaft 46, which has a slotted-link connection 70 47 with the adjacent end of the manifold 25. The cam-action produces the advance-movement of the manifolds 25 and 38 correspondingly with the movement of the endless carrier to maintain the jetting of water into the 75 respective bottles for a desired length of time, whereupon these manifolds are quickly retracted to their initial positions to be again advanced in the same way.

In the tank there extends, below the manifolds 25 and 38, inclinedly from one side thereof short of the opposite side, a shed 48 for catching the labels washed from the bottles and shedding them by the flow of water from above into the body of water 80 in the tank, traversing across the bottom of which extends (Fig. 4) a valved drain-pipe 49 for draining the tank when desired. Baffle-plates 50, 51 and 52 extend lengthwise of the tank below the shed into the 85 water, the central baffle-plate having a hinged gate 53 on its lower end to extend it to the tank-bottom, and permit the gate to be raised for cleaning out, when required, labels and other refuse-matter deposited on 90 the tank-bottom, through manholes one of which is shown at 54 in a side of the tank. Adjacent to the baffle-plate 52 is formed a compartment 55 which determines the 95 water-level in the tank. An endless conveyor 56 formed of successively overlapping perforated plates fastened at their ends to opposite endless chains 56^a is supported to travel through the compartment 55 and below the tank on sprockets indicated at 100 57 journaled on shafts at opposite ends of the tank. One of these sprocket-shafts carries a worm-wheel 58, with which meshes a worm 59 on the adjacent end of the drive-shaft 33; and this same sprocket-shaft carries a pulley 60 (Fig. 6) having an endless-belt connection with a rotary brush 61 journaled on the lower of two tracks 62 along 105 which the conveyer 56 travels to be in position to brush off label-matter adhering to 110 the conveyer 56. Water and labels falling upon the shed 48 are washed into the tank to one side of the baffle-plate 50 and much of the label matter sinks and stays on the 115 tank-bottom, to be taken out at the man- 120

125

holes 54. Such portions of the labels as are carried with the solution past the baffle-plates 51 and 52 into the compartment 55 are intercepted by and deposit gently on the conveyor 56 because of the gentle flow of the solution carrying such matter, and will therefore not be forced through the perforations in the conveyor-plates. In Fig. 6 is shown a bent pipe 63 leading from the inner 10 wall of the tank-compartment 10 lengthwise through the compartment 9 and terminating beyond the latter in a valved spout 64. This pipe takes rinsing water from the compartment 10 to flow it against the traveling conveyor 56 and wash label and other refuse-matter off the latter, while the rotating brush 61 cooperates to loosen such matter adhering to the perforated plates. By thus 20 passing through the hot water in the compartment 9 the cold rinsing water, the latter becomes heated and is thus better adapted for its purpose in cleaning the perforated conveyor-plates; and, besides, by taking heat out of the water in the compartment 9 it tends to prevent excessive heating of that water by the steam employed for the described injecting purpose. As the carrier 12 brings the washed and rinsed bottles to the chute 15 they fall out of the pockets 17 30 upon and slide down the chute to be caught by an attendant.

By means of my improved features thus described, the injector-action of the steam not only greatly reduces the work of pumping, enabling a single pump to be used for operating the machine, but in effecting that saving the further advantages are afforded of causing the steam to keep the nozzles clear and to heat the washing water, besides 40 forcing the water at a high speed into the bottle with resultant enhancement of its cleansing effect. Furthermore, by avoiding intermittent motion of the bottle-conveyor and causing it to travel steadily and 45 uninterruptedly, and moving the injector-nozzles along with the bottles, as described, the washing of bottles is performed in a thorough manner much more speedily, and enables the length of the machine to be 50 materially reduced over one wherein the same work is performed in a machine wherein an intermittently moving bottle-conveyor is employed. Moreover, the means provided for removing refuse-material from the machine adds greatly to its efficiency.

I realize that considerable variation is possible in the details of construction thus specifically shown and described, and I do not intend, by illustrating a single, specific 60 or preferred embodiment of my invention to be limited thereto, my intentions being in the following claims to claim protection upon all the novelty there may be in my invention as broadly as the state of the art 65 will permit.

What I claim as new and desire to secure by Letters Patent is:

1. In a bottle-washing machine of the character described, the combination of a tank, an endless carrier movable lengthwise over the tank and provided with supports for bottles in inverted position, means including a motor for driving said carrier, a motor-driven pump connected at its suction-side with the tank, water-tubes supported to 70 extend at intervals crosswise over the tank below the upper section of said carrier and communicating with the discharge-side of the pump, nozzles projecting upwardly from said tubes, and steam-tubes extending along 75 said water-tubes and provided with jets coinciding and coöperating with said nozzles.

2. In a bottle-washing machine of the character described, the combination of a tank, an endless carrier movable lengthwise over the tank and provided with supports for bottles in inverted position, means including a motor for driving said carrier, a motor-driven pump connected at its suction-side with the tank, a manifold for the wash-water supported to extend over the tank along one side thereof below the upper section of said carrier and communicating with the discharge-side of the pump, a manifold 95 for steam extending along the opposite side and over the tank, water-tubes extending at intervals at the inner side of said first-named manifold and provided with upwardly projecting nozzles, and steam-tubes 100 extending along said water-tubes from the steam-manifold and provided with jets coinciding and coöperating with said nozzles.

3. In a bottle-washing machine of the character described, the combination of a tank, an endless carrier movable lengthwise over the tank and provided with supports for bottles in inverted position, means including a motor for driving said carrier, a motor-driven pump connected at its suction-side with the tank, a manifold for the wash-water supported to extend over the tank along one side thereof below the upper section of said carrier and communicating with the discharge-side of the pump, a manifold 115 for steam extending along the opposite side and over the tank, water and steam-tubes connecting said manifolds at intervals and being formed in pairs having their members parallel and integral with each and closed at respectively opposite ends, nozzles projecting upwardly from the water-tubes and jets extending from said steam-tubes into and coöperating with said nozzles.

4. In a bottle-washing machine of the character described, the combination of a tank, an endless carrier movable lengthwise uninterruptedly over the tank and provided with supports for bottles in inverted position, a motor-driven pump connected at its 130

suction-side with the tank, manifolds reciprocably supported to extend opposite each other lengthwise of the tank below the upper section of said carrier and connected respectively with the discharge-side of the pump and a steam-supply, water and steam tubes extending respectively from said manifolds in pairs crosswise of the tank, nozzles projecting upwardly from said water-tubes, jets extending from said steam-tubes to coincide and coöperate with said nozzles, and motor-driven means for driving said carrier and moving said manifolds correspondingly in one direction with the movement of the carrier and quickly returning them to their initial position.

5. In a bottle-washing machine of the character described, the combination of a tank, an endless carrier movable lengthwise uninterruptedly over the tank and provided with supports for bottles in inverted position, a motor-driven pump connected at its suction-side with the tank, series of rollers supported on the opposite walls of the tank near its top, manifolds reciprocably supported on said rollers and connected respectively with the discharge-side of the pump and a steam-supply, water and steam tubes in pairs of integral members extending respectively from and connecting said manifolds at intervals, nozzles projecting upwardly from said water-tubes, jets extending from said steam-tubes into said nozzles at their bases, a worm-driven connection between said motor and carrier for driving the latter, and means coöperating with said connection to move said manifolds on their supporting-rollers correspondingly in one direction with the movement of the carrier and quickly return them to their initial position.

10. In a bottle-washing machine of the character described, the combination of a tank, an endless carrier movable lengthwise uninterruptedly over the tank and provided with supports for bottles in inverted position, a motor-driven pump connected at its suction-side with the tank, manifolds reciprocably supported to extend opposite each other lengthwise of the tank below the upper section of said carrier and connected respectively with the discharge-side of the pump and a steam-supply, water and steam tubes in pairs connecting said manifolds at intervals, nozzles projecting upwardly from said water-tubes, jets extending from said steam-tubes into said nozzles at their bases, a worm-drive connected with the motor-shaft and geared to the carrier for driving the latter, and a cam-operated link and lever connection between said worm-drive and manifolds coöperating with said worm-drive to move the manifolds correspondingly in one direction with the movement of the carrier and quickly return them to their initial position.

7. In a bottle-washing machine of the character described, the combination with a tank provided with a traveling bottle-carrier and means for washing bottles on the carrier, of a laterally-inclined shed, upright baffle-plates and a compartment below the shed all extending in the tank lengthwise thereof, a refuse-carrier supported to travel lengthwise through said compartment, and means for driving said refuse-carrier.

8. In a bottle-washing machine of the character described, the combination with a tank provided with a traveling bottle-carrier and means for washing bottles on the carrier, of a laterally-inclined shed, upright baffle-plates and a compartment below the shed all extending in the tank lengthwise thereof, a refuse-carrier, comprising endless chains and a series of perforated plates connecting them, supported to travel lengthwise through said compartment, and means for driving said refuse-carrier.

9. In a bottle-washing machine of the character described, the combination with a tank containing hot wash-water and cold rinsing-water compartments in succession and provided with a traveling bottle-carrier and means for washing bottles on the carrier, of a valved pipe extending in the hot wash-water compartment from the rinsing-water compartment for conducting cold water from the latter through and reducing the temperature of the hot wash-water.

10. In a bottle-washing machine of the character described, the combination with a tank containing hot wash-water and cold rinsing-water compartments and provided with a traveling bottle-carrier and means for washing bottles on the carrier, of a compartment extending lengthwise in the tank, a refuse-carrier supported to travel lengthwise through said last-named compartment, means for driving said refuse-carrier and a valved pipe extending from said rinsing-compartment through said hot-water compartment and discharging against said refuse-carrier outside the tank.

11. In a bottle-washing machine of the character described, the combination with a tank containing hot wash-water and cold rinsing-water compartments and provided with a traveling bottle-carrier and means for washing bottles on the carrier, of a compartment extending lengthwise in the tank, an endless refuse-carrier supported to travel lengthwise through said last-named compartment, a brush rotatably supported in the path of said carrier beneath the same outside the tank, a valved pipe extending from said rinsing-compartment through said hot-water compartment and discharging downwardly against said refuse-carrier above said brush, and means for driving said refuse-carrier and brush.

12. In a bottle-washing machine of the

character described, the combination with a tank for the washing water provided with a traveling bottle-carrier, a pump for circulating the water to and from the tank and **6** a motor for operating the pump and connected with said carrier for driving it, of a compartment extending lengthwise in the tank, and an endless refuse-carrier support-
ed to travel lengthwise through said last-named compartment and geared to said bot- **10** tle-carrier driving means to be driven thereby.
